(57) **CLAIM**

The ornamental design for a webcam, as shown and described.

DESCRIPTION

FIG. 1 is a top, front and right side perspective view of a webcam showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is an enlarged view of portion 8 shown in FIG. 2; and, FIG. 9 is an enlarged view of portion 9 shown in FIG. 7. The broken lines in the drawings depict portions of the webcam that form no part of the claimed design; and the dot-dash-dot lines encircling an enlargement portion of the design forms no part of the claimed design.
